SUCTION CLEANER

Donald G. Smellie, Canton, Ohio, assignor to The Hoover Company, North Canton, Ohio, a corporation of Ohio

Application August 9, 1946, Serial No. 689,382

9 Claims. (Cl. 183—35)

1

The present invention relates to suction cleaners in general and more particularly to a new and novel arrangement of parts in a suction cleaner wherein some of the dirt in a dirt-laden air stream is removed prior to filtering the dirt-laden air stream.

It is an object of the present invention to provide a new and improved suction cleaner. Another object is to provide a suction cleaner for separating some of the dirt from a dirt-laden air stream prior to passing the dirt-laden air through a filter. A further object is to provide a suction cleaner wherein the incoming dirt-laden air stream passes a deflecting baffle which causes heavy dirt particles in the air stream to be deflected into a dirt receptacle prior to filtering the air stream. A still further object is to provide an end cap for a suction cleaner casing and having a plurality of separate dirt chambers for collecting different types of dirt. Other objects and advantages of the invention will be apparent from the following specification and drawings wherein:

Figure 1 is a vertical section along the line 1—1 of Figure 3;

Figure 2 is a section along the line 2—2 of Figure 1;

Figure 3 is a section along line 3—3 of Figure 1; and

Figure 4 is a perspective view of the end cap forming the dirt container removed from the suction cleaner casing.

The embodiment of the invention herein disclosed comprises a suction cleaner casing formed in two sections 9 and 10 joined together by a plurality of screws 11. The exhaust end of the cleaner casing is closed by a removable end cap 12 provided with a port 13, and the opposite end is closed by an end cap 14 which includes a dirt receptacle, and the casing is supported upon a pair of runners 15. A transverse wall 16 extends across the casing and is provided with an annular shoulder 17 on which is riveted a cylindrical casing 18 which extends horizontally forwardly into the casing section 10 and forms with the transverse wall 16 a vortical whirl chamber 19. The whirl chamber 19 is provided with a tangential inlet 20 extending outwardly beyond the casing section 10 to a point thereabove and is connected with a conduit 21 formed by a member 22 provided with marginal flanges 23 which are secured to the casing section 10. The conduit 21 extends forwardly beyond the end of the casing section 10 for connection with an unshown dusting tool hose provided with a surface-cleaning nozzle.

2

Formed integral with the transverse wall 16 is an elongated inlet 25 which extends horizontally into the whirl chamber 19 and is provided at its outer end with a strainer plate 26. The opposite end of the inlet 25 extends beyond the transverse wall 16 and is connected to a housing 27 forming a fan chamber. The fan chamber is divided into a first stage 28 opening directly into the inlet 25 and into a second stage 29 by a rigid deflector 30 which includes a multiplicity of vanes 31 and an inlet 32. Within the fan housing 27 are two fans 33—33 of a double stage fan carried by the extended shaft 34 of an unshown motor positioned in a housing 35. The fan chamber in its second stage 29 is provided with a plurality of exhaust ports 36 which connect the fan chamber with a final filter chamber 37, the outer wall of which is defined by a cylindrical filter 38 of suitable air-permeable dirt-impermeable material which is positioned concentrically with the casing section 9. One end of the filter 38 is supported adjacent the fan chamber by an encircling collar 39 which is sealed to the fan chamber housing 27. The opposite end of the filter 38 is mounted on a plate 40 carried in spaced relationship to the casing section 9 by a plurality of spiders 41, and the plate 40 is centrally flanged at 42 to seat on the motor housing 35. The filter 38 and the end plates 39 and 40 define the final filter chamber 37. The space between the casing section 9 and the filter 38 forms an annular discharge chamber 44 which is opened around the plate 40 to apertures 45 formed in the motor housing 35.

The motor housing is supported intermediate its ends by a member 46 having an internal flange 47 in seating engagement with the motor housing 35 and an outer flange 48 in seating engagement with the interior of the casing section 9. The member 46 is provided with spaced openings 49 through which the air from the discharge chamber 44 may pass. The rear end of the motor is supported in a rubber ring 51 seated in a metal frame 52 attached to the casing section 9 by a plurality of screws 53. A removable member 54 cooperates with the motor rear support frame 52 to define an annular chamber 55 in which is disposed a filtering material 56. The motor-supporting frame 52 and member 54 are provided with a plurality of apertures 57 for the passage of air through the filtering material 56 to remove any dirt which might remain in the air.

The driving motor is provided with incoming power leads 58 which pass through a switch-supporting bracket 59 to a manually operable switch 59 from which a pair of leads 67 extend and are

connected to the motor. A handle 68 for carrying the cleaner is mounted between the switch-mounting bracket 58 and the inlet conduit member 22.

A filter-cleaning unit is provided for the filter 38 and comprises a nozzle 60 carried by a conduit 61 mounted for rotation about a sleeve 62 on a bearing 63. Nozzle 60 and its conduit 61 are rotated by the motor shaft 34 through the agency of certain power-transmitting speed-reducing means provided within the casing 64 and which in their specific construction form no part of this invention. The conduit 61 opens into a conduit 65 immediately adjacent the end and side walls of the fan chamber 27 and connects to the whirl chamber 19 at 66 so that at all times, with the cleaner in operation, the conduit 65 is supplied with any suction which is present and available to the whirl chamber 19.

The end cap 14 is provided with a handle 69 and is removably telescopically arranged within the casing section 10 by a pair of latches 79, and comprises a bottom wall 70, vertical side walls 71-71 which merge into an arcuate top wall 72, an outer end wall 73, and an inner end wall 74. Inner end wall 74 extends upwardly from the bottom wall 70 and terminates in an annular seat 77 which telescopes the whirl chamber casing 18 and abuts a gasket 78.

A dirt-collecting chamber 80 for the relatively light particles of dirt discharged from the vertical whirl chamber 19 is formed by the whirl chamber casing 18 and the end walls 73 and 74, vertical side walls 71, and the bottom wall 70 of the end cap 14. An annular dirt discharge outlet 81 from the whirl chamber 19 to the dirt chamber 80 is formed by a member 82 depending from the top wall 72 of the end cap 14 and the extreme end of the whirl chamber casing 18.

A dirt chamber 83 for receiving relatively heavy particles of dirt is formed in the upper portion of the end cap 14 and is provided with an opening 84 which, when the end cap is attached to the cleaner casing, is aligned with an opening 85 in the inlet conduit 21. Formed in the conduit 21 and transversely thereof is a deflecting baffle 86 which is positioned opposite the openings 84 and 85 to engage the incoming dirt-laden air stream and deflect the relatively heavy dirt particles from the air stream into the dirt chamber 83 prior to the air stream entering the vertical whirl chamber 19.

In the operation of the cleaner an unshown dusting tool hose with a cleaning nozzle at its end is attached to the inlet conduit 21 and the motor energized by closing the switch 59. Current passes through the driving motor and the motor shaft 34 rotates the suction-creating fans 33 and the speed-reducing mechanism within the casing 64. The rotation of the suction-creating fans 33 creates a reduced pressure within the whirl chamber 19 which is in turn effective in the inlet conduit 21 and the dusting tool hose and nozzle attached thereto and also within the conduits 65 and 61 and so to the filter-cleaning nozzle 60. As the operator moves the surface-cleaning nozzle over the surface being cleaned, the incoming flow of air carries dirt and foreign material into the inlet conduit 21. Prior to the dirt-laden air entering the whirl chamber 19, the dirt particles in the air stream strike the deflecting baffle 86 which in turn retards the flow of the heavy dirt particles and directs the latter downwardly through the openings 85 and 84 into the heavy dirt-collecting

chamber 83 to thereby remove substantially all of the heavy dirt particles in the incoming air stream. The dirt remaining in the air stream is relatively light in weight and then passes on through the opening 20 into the whirl chamber 19. The light foreign material is thrown by centrifugal force to the periphery of the whirl chamber casing 18 and as it rotates it is forced outwardly by the new incoming air and makes its exit from the forward end of the whirl chamber 19 through the annular discharge opening 81 into the light dirt-collecting chamber 80 arranged about the whirl chamber casing 18.

The cleaned air is drawn through the inlet 25 into the fan chamber and is exhausted therefrom through the exhaust ports 36 into the filter chamber 37. This air which enters the filter chamber 37 is nearly clean and carries only a small percentage of the total dirt which enters the machine, yet a part of which is objectionable to the user as it is capable of creating a dust smell in any escaping air. Whatever foreign material is carried in the air as it enters filter chamber 37 is removed therefrom as the air passes outwardly through the enclosing cylindrical filter 38 into the discharge chamber 44. From the discharge chamber 44 some of the air passes through the apertures 45 and 90 in the motor housing 35 and also exteriorly of the motor housing through the openings 49 in the motor-supporting frame 46 and then through the rear filter 56 and finally through the exhaust port 13 in the end cap 12.

As stated, the suction of the machine is effective within the nozzle 60 which, during operation, is rotated about the motor axis under the actuation of the speed-reducing mechanism within the casing 64. The nozzle 60 is of substantially the same length as the width of the filter 38 and as it moves in its orbit it contacts the entire inner surface of the filter 38 and removes therefrom, by virtue of the flow of cleaning air which is drawn from the discharge chamber 44 backwardly into the nozzle 60, all foreign material which has collected upon the filter 38. This foreign material is conveyed through conduits 61 and 65 to the whirl chamber 19 and again enters the incoming dirt-laden air stream and this time in its passage through the whirl chamber 19 all of the dirt is removed. This operation of the filter-cleaning nozzle 60 is continuous and serves to maintain the back pressure in the filter chamber 37 at a reasonable point and one which does not restrict in an objectionable manner the flow of cleaning air through the machine.

In due time it will become necessary to empty the dirt chambers 80 and 83 in the end cap 14. This is accomplished by manually releasing the latches 79 upon the opposite side of the casing section 10 of the suction cleaner. Thereafter the operator, by grasping the handle 69, can remove the end cap 14 from the cleaner casing and by inverting the end cap the heavy dirt particles in the dirt chamber 83 and the light dirt particles in the dirt chamber 80 are removed. After emptying the dirt from both of the chambers 80 and 83 the end cap 14 is replaced in the cleaner casing and the latches 79 manipulated to lock the dirt receptacles and end cap in position, and the cleaner is then again ready for operation.

I claim:

1. In a suction cleaner, suction-creating means for drawing a dirt-laden air stream into

said cleaner, a dirt-receiving container means extending into the path of said dirt-laden air stream for deflecting some of the dirt laterally therefrom into said dirt-receiving container, and a stationary dirt separator of the whirl type interposed between said dirt-receiving container and said suction-creating means for removing dirt remaining in said air stream prior to the latter passing through said suction creating means.

2. In a suction cleaner, suction-creating means for drawing a dirt-laden air stream into said cleaner, a conduit for conveying said dirt-laden air stream toward said suction-creating means, a dirt-receiving container having an entrance connected to said conduit, means in said conduit in the path of said dirt-laden air stream and at said entrance to said dirt-receiving container for deflecting laterally some of the dirt from said air stream into said dirt-receiving container, and a stationary dirt separator of the whirl type interposed between said dirt-receiving container and said suction-creating means for removing dirt remaining in said air stream prior to the latter passing through said suction creating means.

3. In a suction cleaner of the type having a casing provided with a stationary dirt separator, and suction-creating means to draw a dirt-laden air stream through said stationary dirt separator; a dirt container removably connected to said suction cleaner casing and having two separate dirt-collecting chambers, one of said dirt-collecting chambers connected to said dirt-laden air stream for receiving relatively heavy dirt therefrom, and the other of said dirt-collecting chambers connected directly to said stationary dirt separator to receive substantially all of the remaining dirt in said air stream.

4. In a suction cleaner of the type having a dirt separator of the vertical whirl type defined by a casing having an open end, and suction-creating means to draw a dirt-laden air stream through said vertical whirl dirt separator; a dirt container removably connected to said suction cleaner and having means spaced from said open end of said vertical whirl casing to define with the latter a discharge outlet for the dirt removed from the dirt-laden air stream, and a dirt-collecting chamber in said dirt container for receiving the dirt from said discharge outlet.

5. In a suction cleaner, a cleaner casing, suction-creating means for drawing a dirt-laden air stream into said cleaner, an end cap removably connected to said casing, a plurality of separate dirt-receiving chambers in said end cap, means for deflecting some of the dirt from said dirt-laden air stream into one of said dirt-receiving chambers, and a stationary vertical whirl type dirt separator interposed between said one dirt-receiving chamber and said suction-creating means for removing dirt remaining in said air stream and discharging it into another of said dirt chambers in said removable end cap.

6. In a suction cleaner, an initial dirt separator, suction-creating means for drawing a dirt-laden air stream through said initial dirt separator, a final dirt separator to receive relatively clean air from said suction-creating means and filter the same, means for removing dirt collected

on said final dirt separator and return it to said initial dirt separator, and means for deflecting some of the dirt from said dirt-laden air stream prior to passing through said initial separator to thereby reduce the amount of dirt to be removed from said air stream by said initial and final dirt separators.

7. In a suction cleaner, a cleaner casing, suction creating means for drawing a dirt-laden air stream into said casing, a dirt container removably attached to said casing and having a plurality of inlets for entrance of dirt into said container, a dirt separator interposed between said inlets, means for deflecting some dirt from said dirt-laden air stream through one of said inlets into said dirt container, said dirt container cooperating with said dirt separator to define the other of said inlets for passage of dirt from said dirt separator into said container.

10 8. A suction cleaner comprising a casing having an open end, a whirl type dirt separator in said casing and exposed in part at said open end, conduit means in said casing for conveying dirt laden air from a surface being cleaned to said dirt separator, suction creating means in said casing for moving said dirt laden air through said conduit means and said whirl type dirt separator, a cover for said casing open end removably attached to said casing, said cover including 15 means forming a first dirt container and means forming a second dirt container, means defining an opening in said conduit means, means in said conduit means deflecting some dirt from said dirt laden air through said opening into said first dirt container prior to passage into said dirt separator, and means on said cover cooperating with said dirt separator, when said cover is attached, to define an inlet for passage of dirt from said dirt separator into said second container.

20 9. A suction cleaner comprising a casing, a whirl type dirt separator in said casing, conduit means for conveying dirt laden air from a surface being cleaned to said whirl type dirt separator, suction creating means in said casing for moving said dirt laden air through said conduit means and then said whirl type dirt separator, a first dirt container connected to said conduit means, means in said conduit means deflecting some dirt from said dirt laden air passing through said conduit means into said first dirt container prior to passage into said whirl type dirt separator, and a second dirt container connected to said whirl type dirt separator for receiving dirt discharged by the latter.
